DESIGN FOR A TOY TRAIN

Lois Lenski Covey, Torrington, Conn.

Application February 21, 1945, Serial No. 118,075

Term of patent 14 years

(Cl. D34—15)

To all whom it may concern:

Be it known that I, Lois Lenski Covey, a citizen of the United States, residing at Torrington, in the county of Litchfield and State of Connecticut, have invented a new, original, and ornamental Design for a Toy Train, of which the following is a specification, reference being had to the accompanying drawing, forming part thereof.

In the drawing,

Fig. 1 is a side elevational view of a toy train showing my new design;

Fig. 2 is a top plan view thereof;

Fig. 3 is a view in side elevation of individual blocks in unassembled relation;

Figs. 4, 5 and 6 are perspective views of individual blocks; and,

Fig. 7 is a fragmentary view in enlarged detail of one of the wheels and associated structure.

I claim:

The ornamental design for a toy train, substantially as shown.

LOIS LENSKI COVEY.
